CLAIM

(73) Assignees: **CHINA-GERMANY(ZHUHAI) ARTIFICIAL INTELLIGENCE INSTI**, Zhuhai (CN); **ZHUHAI 4DAGE TECHNOLOGY CO., LTD.**, Zhuhai (CN)

The ornamental design for a display screen with graphical user interface, as shown and described.

DESCRIPTION

(**) Term: **15 Years**

FIG. 1 shows a first image in a sequence for a display screen with transitional graphical user interface, according to the new design.

(21) Appl. No.: **29/741,497**

FIG. 2 shows a second image thereof.

(22) Filed: **Jul. 13, 2020**

FIG. 3 shows a third image thereof.

(30) **Foreign Application Priority Data**

FIG. 4 shows a fourth image thereof.

Jun. 12, 2020 (CN) 202030305848.1
(51) LOC (13) Cl. **14-04**

FIG. 5 shows a fifth image thereof.

(52) U.S. Cl.

USPC **D14/486**

FIG. 6 shows a sixth image thereof.

(58) **Field of Classification Search**

FIG. 7 shows a seventh image thereof.

USPC D14/485-495
CPC G06N 3/04; G06N 3/08; G06T 19/006;
H04N 5/232; H04N 13/204

FIG. 8 shows an eighth image thereof.

See application file for complete search history.

FIG. 9 shows a ninth image thereof.

(56) **References Cited**

FIG. 10 shows a tenth image thereof.

U.S. PATENT DOCUMENTS

FIG. 11 shows an eleventh image thereof.

D708,192 S 7/2014 Francis
D722,615 S * 2/2015 Walkin D14/488

FIG. 12 shows a twelfth image thereof.

FIG. 13 shows a thirteenth image thereof.

FIG. 14 shows a fourteenth image thereof; and,

FIG. 15 shows a fifteenth image thereof.

The appearance of the transitional image sequentially transitions between the images shown in FIGS. 1-15. The process or period in which one image transitions to another image forms no part of the claimed design.

The outer broken lines showing a device, and the inner broken line rectangle showing a display screen, illustrate portions of the article and form no part of the claimed design.

1 Claim, 15 Drawing Sheets
